[57] CLAIM

The ornamental design for a toy desk, as shown and described.

DESCRIPTION

FIG. 1 is a front elevational view of a toy desk showing my new design;

FIG. 2 is a right side elevational view thereof, the side opposite being substantially a mirror image;

FIG. 3 is a top plan view thereof;

FIG. 4 is a bottom plan view thereof;

FIG. 5 is a rear elevational view thereof; and

FIG. 6 is a top perspective view thereof showing the design in an open condition.

FIG. 1

FIG. 2

FIG. 3

FIG. 4

FIG. 5

FIG. 6
